[57] CLAIM

The ornamental design for a detachable toothbrush head and
handle unit, as shown and described.

DESCRIPTION

FIG. 1 is an exploded view of a detachable toothbrush head
and handle unit showing my new design;
FIG. 2 is an assembled right side view thereof;
FIG. 3 is a top view thereof;
FIG. 4 is a bottom view thereof;
FIG. 5 is a front view thereof; and,
FIG. 6 is a rear view thereof.
The left side is a mirror image of the right side.
